UNITED STATES PATENT OFFICE

96,682

DESIGN FOR A HAND BAG

Isidore Lending, New Bedford, Mass., assignor to Sol Mutterperl, Inc., New York, N. Y., a corporation of New York

Application February 14, 1935, Serial No. 55,436

Term of patent 3½ years

To all whom it may concern:

Be it known that I, Isidore Lending, a citizen of the United States, residing at New Bedford,
in the county of Bristol and State of Massachusetts, have invented a new, original, and ornamental Design for Handbags, of which the following is a specification, reference being had to the accompanying drawing, forming part thereof.

Figure 1 is a perspective view of the handbag
in a closed position, showing my new design.

Figure 2 is a perspective view drawn on a slightly smaller scale of said handbag in an open position.

The back of the handbag shown in Figure 1 is substantially the same as the front.

I claim:

The ornamental design for a handbag, as shown and described.

ISIDORE LENING.
